UNITED STATES PATENT OFFICE.

ERNEST M. SKINNER, OF BOSTON, MASSACHUSETTS.

ELECTROPNEUMATIC SWELL-PEDAL ACTION FOR PIPE-ORGANS.

1,076,069.

Specification of Letters Patent. Patented Oct. 21, 1913.

Application filed September 9, 1911. Serial No. 648,547.

To all whom it may concern:

Be it known that I, ERNEST M. SKINNER, of Boston, in the county of Suffolk, and State of Massachusetts, have invented certain new and useful Improvements in Electropneumatic Swell-Pedal Actions for Pipe-Organs, of which the following is a specification:

The object of this invention is to eliminate the uncertainty and erratic behavior that 10 has always attended these mechanisms.

The usual construction of an electropneumatic mechanism for operating swell shutter consists in a bellows for closing the shutter, and another connected thereto for opening it. Inasmuch as it is necessary for these shutters to move in either direction, to rest at intermediate points and to move at various speeds, a controlling mechanism consisting of cutouts, neutral points, systems of 20 contacts for opening, systems of contacts for closing, etc., has always been indispensable; a valve sufficiently large to carry a swell pneumatic its entire excursion in a very brief space of time is not suitable for moving the 25 same pneumatic a short distance and at a slow speed.

The present invention aims to solve all these problems, to eliminate all the elements of uncertainty, all contacts, neutral points, 30 places of adjustments, etc., at the motors, and to substitute a more reasonable and tractable mechanism.

One of the purposes of this invention is to provide an engine or motor for actuating 35 the swell shutter, of which the power shall vary with the amount of work to be done at the moment and by means of which, without regard to the speed or direction of movement, any definite or certain number of contacts in circuit at the swell shoe will always give exactly the same position of the engine and swell shutter.

With the above and other objects in view, as will presently appear, the invention consists in the novel construction of the parts 45 of the swell pedal mechanism, hereinafter fully described and claimed in the following description.

In the accompanying drawings forming a 50 part of this specification, in which like characters of reference indicate corresponding parts in all views, there is illustrated a form of embodiment of the invention capable of carrying the same into practical operation, 55 it being understood that the elements therein exhibited may be varied as to shape, proportion, detail and exact manner of assem-

blage without departing from the spirit thereof.

In the drawings Figure 1 is a diagrammatic view illustrating the organ in use, having wind in the chest, the swell shutter being completely closed. Fig. 2 shows a cross section of the swell shutter in the closed position. Fig. 3 shows the same in the open position. Fig. 4 is an enlarged section of the pneumatic engine's ring motor in detail a part of the devices shown in Fig. 1. Fig. 5 is an enlarged view of the group of pneumatic motors 5, with their connecting bars 6. Fig. 6 is a plan of a usual arrangement of the pneumatic motors, viewed from beneath. Fig. 7 is a diagram showing three of the pneumatic motors 5 in operation. Fig. 8 is a diagram showing one of the 75 pneumatic motors 5 in operation. Fig. 9 is an enlarged sectional view illustrating the valve mechanism.

The same reference characters indicate the same parts in all the figures. 80

One of the chief difficulties in the employment of two opposed motors in devices of the description cited above has been the variability of the load. In the engine herein described, the load is always the same on each motor; if the shutter is to be moved a short distance only one or two motors will be actuated. If the shutter is to be moved suddenly the entire distance, all the motors will be actuated at once, and as all the motors may be collapsed or inflated in the same amount of time required for any one of them to operate, a promptness is secured which is not obtainable with mechanism of the older forms. 95

Referring first to Fig. 1, I have represented by 1 a foot lever or pedal normally held in the position illustrated and adapted to be depressed about a pivotal axis 2 by pressure of the performer's foot. This pedal 100 is connected by means of a link 3 with a lever 4, which is one contact member of an electric switch. This lever is adapted to engage and make electrical connection with a number of complementary contacts 5, which are so arranged as to be engaged successively by downward movement of the switch lever 4, being thus engaged one at a time. The switch lever 4 is connected with one terminal 6 of an electric battery, 7, or other 110 source of electrical energy. The other terminal 8 of this battery or source of energy is provided with branches 9 which lead respectively to independent electro-magnets,

one of which is shown in Fig. 4 and is hereinafter described. The several complementary switch contacts 5 are independently connected electrically with the windings of the several electro-magnets to which the branches 9 lead. The wires making such connections are gathered into a cable 10. 12 represents a chest or wind box which is kept permanently supplied with compressed air from a bellows or other compressor. A pipe or conduit for conducting the compressed air to the chest is indicated at 13. In the chest are pneumatic motors 14, there being a series of such motors from two to 15 eight or more, and all alike in respect to the power and extent of motion which they can produce. In form each of such motors is similar to bellows having a rigid top 15, which is secured to the top of the wind box, and a movable bottom 16 exposed to the 20 pressure of air in the wind box. The top and bottom of each bellows are connected by flexible sides which permit movement of the bottom. From the interior of each motor 25 extends a passage 17 from which outlets lead respectively to a windway 18 continuously in communication with the wind box, and to the outer air. These outlets are controlled by valves 19 and 20 respectively. Each of the motors is governed in its action 30 by an electro-magnet 21, which, through its armature 22 and pneumatic 23, valve 24 and pneumatic 25, actuates the valves 19 and 20 in a manner well-known in the art, so as to close either the valve 19 or the valve 20 and simultaneously open the other, according 35 as the magnet circuit is opened or closed. The magnets 21 for the motors are those previously referred to as being in circuit with the battery 7 and the switch contacts 4 and 5. Fig. 1 illustrates the normal positions of the motors whether the chest is full of wind or when the organ is entirely 40 at rest. In other words the positions of the motors do not change except when the 45 circuits are closed by the switch 4.

In Figs. 1, 2 and 3, 26 represents the swell shutter, which is shown as closed in Figs. 1 and 2, and as fully opened in Fig. 3. This 50 shutter comprises pivotally mounted sections all connected to a rod 27 which, when moved endwise in one direction or the other, opens or closes the sections respectively. A link 28 is connected with the rod 27 and 55 with a bell crank lever 29. One arm of the latter is attached to a rod or wire 30, passing through the bottom of the wind chest and supporting a weight 31 or the equivalent thereof, which tends to draw it downward. The wire or rod 30, which, for convenience of description, I may refer to as the tie, is connected with all of the motors 14 by means of a system of bars or floating levers 32, 33 and 34. The tie is connected 60 at the middle of the bar 32, which at its

ends is suspended flexibly from the middle of two bars 33, and the latter at their ends being suspended in like manner from the middle of bars 34. Each of the last-named bars is in like manner connected flexibly 70 with two of the motors. Thus it will be seen that these floating levers act as equalizers. The tie 30 passes through an opening 35 in the bottom of the chest 12, from which escape of air is prevented by a packing 36 75 of a character common in this art.

From the foregoing it will be seen that the movement of all of the motors simultaneously through their full extent gives the maximum movement to the tie, and consequently to the swell shutter, while independent movement in one of the motors gives only a fractional part of such movement to the tie. The denominator of such fraction is the number of motors employed. As here shown there are eight motors, but in practice I contemplate using twice as many, arranged in the wind box and connected together by an additional bar similar to the bar 32 below the box from which the tie 30 is suspended. I have only shown one set of eight such motors with the connections, because such showing sufficiently illustrates the principle of the invention, and also to simplify the drawings.

A study of the system of bars and their connections will make it clear that the movement of any one of the motors is equal to the total movement of the perpendicular tie, and it follows that if there are eight motors, each one of them will bear one-eighth of the load; if sixteen, which is usual in practice, each motor will bear one-sixteenth of the load. It should also be clear that a sudden movement of the shutter from one extreme position to another occasions no greater load on any one of the motors than a lesser movement, since a variation in the speed or extent of the movement of the shutter means only the employment of a greater or less number of motors for the purpose.

Fig. 8 shows one of the motors collapsed, and the effect of its movement indicated on the scale opposite the perpendicular tie, i. e., it has raised said tie one-eighth the total distance.

Fig. 7 shows three of the motors collapsed, and the position assumed by bars in raising the perpendicular tie three eighths its total movement. In mechanism designed for this purpose, it is customary to use an "open circuit" system of electric contacts and wiring, the circuits being completed at contact lever 4 by the usual on and off contacts, and automatically broken at the pneumatic mechanism operating the swell shutters. In the device herein described the circuits are always complete at the mechanism controlling the shutter, the make-and-break being 125

made only at contact points, 4 and 5, thereby eliminating a great amount of troublesome complication.

The operation is as follows: The motors 5 serve to close the shutter, the weight or spring 31 to open them. Thus when the organ is not in use the said weight or spring holds all of the motors expanded and the shutters 26 open. When the organ is 10 in use, however, and the magnets are all de-energized, the pressure of the fluid entering box 12 through pipe 13 maintains all the motors 14 in a collapsed condition and the shutter 26 closed as illustrated in Fig. 1. If 15 the foot piece 1 be now depressed, a resulting lowering of contact piece 4 will take place and one of the contacts 5 will be closed, one of magnets 21 will be energized. Referring to Fig. 9 it will be seen that when magnet 21 is energized, the armature 37, which also acts as a valve is drawn so as to uncover passage *a* and cover passage *h* thereby placing the chamber on the right of diaphragm 23 in communication with the atmosphere 20 through passages *a*, *b* and *c*. The fluid pressure in chamber *d* being greater than atmospheric pressure, the diaphragm 23 is moved to the right just as soon as the passage *a* is 25 opened. This movement causes the valve 24 to uncover passage *f* and cover passage *e*. The chamber to the left of diaphragm 25 is thus opened to the atmosphere through passage *f*, 38 and *g*, whereupon the pressure in chamber *d* causes diaphragm 25 to move 30 to the left unseating valve 19 and seating valve 20. The pressure from chamber *d* then enters the bellows 14 through passage 17. The internal and external pressures on the bellows then being equal, the weight or 35 spring 31 acts to open the bellows, and shutter 26 will accordingly be opened one eighth its traveling distance; a further depression of contact piece 4 results in a similar operation of the remaining 40 motors, until all are inflated and the shutter is entirely open. When the magnet 21 is deenergized the pressure in chamber *d* causes the armature to close passage *a*, and open passage *h*, whereupon the fluid under 45 pressure in chamber *d* passes through passages *h*, *b* and *c* to the right side of diaphragm 23, moving the latter to the left, causing the valve 24 to close passage *f* and open passage *e*. This permits the fluid 50 under pressure in chamber *d* to pass through the passages *e*, 38 and *g* to the left of diaphragm 25, moving the latter to the right to close valve 19 and open valve 20. The 55 interior of the bellows 14 is thus opened to the atmosphere, and the greater fluid pressure in chamber 12 causes the bellows to collapse, effecting a corresponding closing movement of the shutter.

I claim—

65 1. An electropneumatic swell pedal action,

comprising a set of motors 14, a bar arranged transversely to the direction of motion caused by said motors, common to said set of motors and connected thereto, one extremity to each motor, a swell shutter having sections arranged to move collectively, and connecting means engaged with an intermediate point of said bar, and connecting said bar to said shutter substantially as described. 75

2. An electropneumatic swell pedal action comprising a group of motors, a group of bars, extending transversely of the direction of motion produced by the motors, certain of such bars being connected near their ends with certain of the motors, and another being connected near its ends with intermediate points on the first bars, a swell shutter provided with a series of sections connected to move together, and a tie connecting said shutter to the last-named of said bars, substantially as set forth. 85

3. An electropneumatic swell pedal action comprising a swell shutter, a group of motors, connecting means engaged with all of said motors at once and with said shutter, magnets, pneumatics and valves controlling the motors independently, a group of contacts each connected in circuit with one of the magnets, and a contact piece in circuit with the magnets adapted to engage with said contacts, substantially as described. 90

4. An electropneumatic swell pedal action comprising a plurality of parallel circuits each provided with contacts, a contact piece arranged to successively engage said contacts to complete the circuits, magnets arranged in the respective circuits, a group of motors controlled independently of each other by said magnets, a swell shutter, motor equalizing mechanism connected with all the motors, and a tie connecting said equalizing mechanism with said shutter. 100

5. A pneumatic swell pedal action comprising a swell shutter, a group of motors, pneumatic means for independently controlling said motors, and a group of bars, connected to each other, and to the motors, means for connecting said bars to said shutter to move the latter in response to movements produced by said motors, and a weight connected to said bars and acting in opposition to the pressure within said motors. 110

6. An electropneumatic swell pedal action comprising a wind-box, a group of motors, a tie-rod issuing from said wind-box, and a flexible packing sleeve surrounding said tie-rod in air-tight connection therewith and with the wind box, a swell shutter connected with said tie-rod, and means for connecting said tie-rod and motors, said means including levers for causing the extent of movement of the tie-rod to be in proportion 125 130

to the number of motors in operation at any one time.

7. An organ swell action comprising a swell shutter, a plurality of duplicate motors, means for energizing the motors separately, connections from said motors to said shutter, said connections including means for varying the extent of movement of the shutter in proportion to the number 10 of motors in use at any one time.

8. An electropneumatic organ swell action, comprising a plurality of separate duplicate pneumatic motors, an electro-magnetic control for each motor, switch contacts 15 in circuit separately with the several controls, a complementary switch member arranged to be successively brought into and out of contact with said contacts, to close and open the circuits of the control and operate the motors successively, a swell shutter, floating levers each connected at its opposite ends to two motors, a further floating lever connected at its ends with two of the first-named levers at the middle points of the latter, a 20 third lever connected with the second lever at the middle point thereof, and a tie connected with the lever at the middle point thereof, and with the shutter, whereby movement of all the motors gives the shutter its 25 maximum movement, and movement of one or more of the motors, less than all, proportionately varies the extent of movement of the shutter.

9. An organ swell action, comprising a 30 swell shutter, a plurality of motors, means for energizing the motors in succession cumulatively, and connecting means between the several motors and the shutter, said connecting means including means for causing 35 the distance the shutter opens to vary in accordance with the number of motors inflated.

10. An electropneumatic swell pedal action, comprising a swell shutter; a group of 45 motors, connecting means engaged with all of said motors at once and with said shutter, a plurality of magnets, pneumatics and valves controlling the motors independently, a plurality of contacts, each being permanently in electrical connection with one of said magnets, and a complementary contact member in electrical connection with all of said magnets and arranged to be successively brought into contact with all of the first 50 named contacts.

11. An electropneumatic swell pedal action, comprising a swell shutter, yielding means tending constantly to open said shutter, a group of motors and connecting means 55 engaged with all of said motors at once and with said shutter, electro-magnetic means for causing operation of the motors in opposition to the action of said yielding means,

and separable contacts in electrical connection with the several electro-magnetic means, 65 said electro-magnetic means being arranged to cause operation of the motors when the circuits are closed.

12. An apparatus of the character described comprising a swell shutter, a plurality of pneumatic motors, each of said motors having a communication with the atmosphere and with a source of air under pressure valves controlling said communications, electro-magnetic means arranged to 70 open the communication of said motors with the atmosphere and simultaneously close that with the source of pressure and vice versa, connecting means between the motors and the shutter, yielding means connected with 75 the said connecting means and tending constantly to open the shutter, said motors being constantly exposed to pressure of air greater than atmospheric, and separable contacts in constant connection with the several 80 magnets, the magnets and the controlling valves operated thereby being so arranged as to close the communication of the shutters with the atmosphere and open that with the source of air under pressure when the magnet 85 circuits are closed, whereby the shutter is caused to open upon closing of the magnet circuits. 90

13. An electropneumatic swell pedal action comprising a pressure chamber, collapsible motors located therein, mechanical means acting normally to expand said motors, means for introducing fluid under pressure into said chamber, said fluid acting normally to collapse said motors in opposition 100 to said mechanical expanding means, means for introducing fluid from said chamber into said motors to equalize the pressure, and swell shutters operatively connected with said motors. 105

14. An electropneumatic swell pedal action comprising a pressure chamber, collapsible motors located therein, mechanical means acting normally to expand said motors, means for introducing fluid under pressure into said chamber, said fluid acting normally to collapse said motors in opposition to said mechanical expanding means, means for introducing fluid from said chamber into said motors to equalize the pressure, a swell 110 shutter, and equalizing mechanism connecting said shutter with said motors to cause said shutter to move a distance equal in proportion to the movement of all of the motors in operation at any one time. 115

In testimony whereof I have affixed my signature, in presence of two witnesses.
